UNITED STATES PATENT OFFICE

162,118

SHOCK MOUNTED CONTAINER

Arthur E. Bausenbach, Buffalo, N. Y., assignor to
A. E. Bausenbach Incorporated, Buffalo, N. Y., a corporation of New York

Application March 28, 1950, Serial No. 8,826

Term of patent 14 years

(Cl. D58—1)

To all whom it may concern:

Be it known that I, Arthur E. Bausenbach, a citizen of the United States, residing at Buffalo, in the county of Erie and State of New York, have invented a new, original, and ornamental Design for Shock Mounted Container, of which the following is a specification, reference being had to the accompanying drawing, forming a part thereof.

The figure is a perspective view of a shock mounted container showing my new design.

The other end and side of the container not shown are similar to the side and end shown in the drawing.

I claim:

The ornamental design for a shock mounted container, substantially as shown and described.

ARTHUR E. BAUSENBACH.
